Primary Examiner — Karen E Kearney*Assistant Examiner* — Katherine Glennon(74) *Attorney, Agent, or Firm* — Brinks Gilson & Lione; John C. Freeman(57) **CLAIM**

The ornamental design for a watch movement, as shown and described.

DESCRIPTION

FIG. 1 is a perspective view of a watch movement according to the present invention;

FIG. 2 is a top view;

FIG. 3 is a bottom side view;

FIG. 4 is a front side view;

FIG. 5 is a rear view;

FIG. 6 is a left side view; and,

FIG. 7 is a right side view.

The ornamental design which is claimed is shown in solid lines in the drawings. The broken lines showing of portions of the article form no part of the claimed design.

1 Claim, 7 Drawing Sheets(56)
